UNITED STATES PATENT OFFICE.

SIMON H. STUPAKOFF, OF HARTFORD, CONNECTICUT.

CARBON-HOLDER FOR ARC LAMPS.

SPECIFICATION forming part of Letters Patent No. 340,065, dated April 13, 1886.

Application filed February 8, 1886. Serial No. 191,112. (No model.)

To all whom it may concern:

Be it known that I, SIMON H. STUPAKOFF, of Hartford, Connecticut, have invented an Improvement in Electric-Arc Lamp Carbon-Holders, of which the following description and claims constitute the specification, and which is illustrated in the accompanying sheet of drawings.

This invention is a mechanism for attaching to the upper carbon to the carbon-rod, or for attaching the lower carbon to its supporter.

Figure 1 is a view of this invention holding an upper carbon to a carbon-rod. Fig. 2 is a central vertical section of the same. Figs. 3 and 4 are horizontal sections of the same on the lines *a a* and *b b*, respectively, of Fig. 2. Fig. 5 is a view of the invention modified in form and holding a lower carbon within its supporter. Fig. 6 is a central vertical section of Fig. 5. Fig. 7 is a central vertical section of the lower-carbon supporter with my invention again modified and holding a lower carbon within the same.

The numeral 1 indicates the upper carbon, 25 and 2 denotes the carbon-rod. The carbon-holder 3 is permanently fixed to the carbon-rod, or it may be fixed with a ball-and-socket joint thereto, and it is provided with a central recess for the reception of the upper 30 end of the upper carbon, and with three converging recesses, 4, 5, and 6, surrounding the central recess, and extending to it from the outer and upper sides of the carbon-holder. These converging recesses all open into the 35 central recess; but those openings are of less diameter than are the converging recesses. The balls 7, 8, and 9 are small enough to work easily in the converging recesses 4, 5, and 6, respectively, and large enough to be unable 40 to pass through the openings into the central recess of the carbon-holder, though they must protrude into that recess through those openings. The shell 10 incloses the spherical part of the carbon-holder 3, and is provided with 45 the downward projections 11, 12, and 13. This shell may be of brass, and may be spun over the carbon-holder, so as to cover the outer ends of the converging recesses and not be removable therefrom; or the spaces which 50 divide the projections 11, 12, and 13 may be continued upward to the equator of the spherical part of the carbon-holder, so as to

be removable therefrom by bending the projections outwardly, or by turning the shell upon the carbon-holder till those projections 55 reach alignment with corresponding grooves cut in the outer surface of the carbon-holder to admit the upward passage of those projections without bending them. So, also, the projections 11, 12, and 13 may be appurtenant to the carbon-holder 3 instead of to the shell 10; or, they may be omitted altogether where the carbon is otherwise sufficiently connected electrically with the carbon-rod.

The lower-carbon supporter 4 is of a common construction, and is provided with the insulating annular-flanged disk 15. The lower-carbon holder 16 rests within that annular disk, and is provided with a central recess, and three converging recesses with balls therein, similar to the corresponding devices in the upper-carbon holder 3. The ring 17, provided with the projections 18, 19, and 20, is fixed with a bayonet-joint to the upper end of the lower-carbon holder, as shown in Fig. 6, or to the lower end thereof, as shown in Fig. 7, or to both ends thereof, if desired by the constructor.

The mode of operation is as follows: The carbon is placed in the carbon-holder by simply inserting it from below; but the three balls act as wedges to prevent its direct withdrawal by gravity or otherwise, while they permit its withdrawal spirally. A single motion of the hand holding the carbon will 80 therefore fix it firmly in the carbon-holder, and a compound pulling and turning motion will readily withdraw it therefrom. The upper carbon is electrically connected with the carbon-rod by direct contact and through the 90 three balls and the upper carbon-holder. The projections 11, 12, and 13 constitute additional electrical connection between the upper carbon and the carbon-rod, while the projections 18, 19, and 20 similarly connect the lower 95 carbon with the line-conductor through the binding-post 21, which binding-post is insulated from the carbon-supporter 14, though mechanically connected therewith.

The three converging channels and their 100 balls may be increased in number and changed in relative position, if desired. Three such balls working on one plane and three others working on another plane produce a good re-

sult, especially when the upper-carbon holder is joined to the carbon-rod by a ball-and-socket joint.

I claim as my invention—

- 5 The carbon-holder 3, provided with a central recess for the reception of a carbon, and with the converging recesses 4, 5, and 6, for the reception of three balls, each converging recess being provided with an opening into

the central recess wide enough to permit the 10 protrusion, but not wide enough to permit the passage of its ball thereout, all substantially as described.

SIMON H. STUPAKOFF.
